UNITED STATES PATENT OFFICE.

JOSEPH HEINZEL, OF GRANTWOOD, NEW JERSEY.

OIL BURNER.

Application filed March 9, 1923. Serial No. 623,836.

To all whom it may concern:

Be it known that I, JOSEPH HEINZEL, a citizen of the United States, residing at Grantwood, in the county of Bergen and 5 State of New Jersey, have invented certain new and useful Improvements in Oil Burners, of which the following is a specification.

This invention relates to heaters, particularly to heaters which use oil or other volatile liquids as a fuel, the main object being to provide a device which may be used in conjunction with any type of stove or furnace, and of such size as to be readily inserted and set up in said articles.

15 Another object is to provide an oil heater in which the surface of a burning pool of oil is atomized by jets of air and water vapor which may be used simultaneously or selectively as desired.

20 These and other objects will become apparent in the description below, in which characters of reference refer to like-named parts in the drawing.

Referring briefly to the drawing, Figure 25 1 is an elevational view showing the method of applying the heater, said heater being shown partly in section.

Figure 2 is a top plan view of the body of the heater, showing the disposition of 30 the air and water vapor jets.

Figure 3 is a sectional elevational view of the device taken on line 3—3 of Figure 2, showing the method of anchoring the hood in place.

35 Referring in detail to the drawing, the numeral 10 indicates the annular wall of the heater body provided with a spherical bottom 11. A concentric funnel 12 having a tapered opening 13 therein, rises vertically 40 from the inner face of the bottom 11. The opening 13 diverges and has its greatest dimension at the upper mouth of the funnel. A semi-circular wall 14 is formed on opposite sides of the funnel and has a channel 15 45 which passes thru the bottom of the body member. A raised boss 16 is formed on the outer wall surface of the body and has the threaded end of a pipe line 17 secured therein. Said pipe line leads to an oil storage 50 tank (not shown), which may be situated at any convenient location. The main body is mounted on a plurality of spaced apart legs 18, the upper end of each leg having a ridge 19 formed thereon which is concentric with the wall 10 but spaced apart therefrom by a channel 20. The latter receive

the annular wall 21 of an inverted cone shaped hood 22 which has a relatively large opening 23 at its upper end. The upper end of the hood wall is provided with a plurality of holes 24 thru which the air can freely circulate. A vaporizer head 25 having a semi spherical surface at its upper end and a substantially flat surface 26 at its lower side, is superposed above the opening 23. A 60 lug 27 at the lower edge of one side of the head has a pipe connected thereto which leads to a convenient water supply system. A similar lug 28 projects from the opposite side of said head tangential with the top of 70 the head and receives one end of the pipe 29. Said pipe passes substantially downwardly with a number of necessary bends, the opposite end 30 projecting into the funnel opening 13, said pipe end 30 being upturned. A chamber 32 is formed beneath 75 the body of the device by a casing 31, said casing communicating with a motor driven blower 33 thru the medium of pipe 34.

In using the heater, the entire device is 80 inserted into the fire box of a furnace or stove and may rest upon the grate thereof. A pipe from a water supply is permanently secured in the lug 27, and a pipe 17 leading from a source of fuel oil supply is similarly tapped into the boss 17. Fuel oil 85 is allowed to flood the chamber 36 in the main body, its level being controlled by a suitable valve so that it will not overflow into the air chambers 15. When the device is to be operated the surface of the oil 90 is ignited and the flames therefrom will pass upwardly and contact with the underside 26 of the water head 25, the latter forming a baffle to said flame and thereby spreading 95 the flame and causing the same to traverse a greater area. The water within the head 25 is simultaneously vaporized and the steam passes out of said head thru the lug 28 and pipe 29. Said steam thence follows the 100 course of the pipe to the top of its open end 30 whence it passes thru the tapered opening 13 and expands over the chamber 36 directly above the liquid. Said steam, 105 besides creating a strong draft, in mixing with the burning oil vapor aids atomization of the same and also gives the flame a higher temperature, which is desired. The flames after passing the water head 25 lead upwardly and heat a water jacket as used in 110 the furnace, or any element which may be above the device.

In practice it has been found that some localities are not readily conducive to the use of steam as an atomizing medium, owing to the suspended deposits of lime and other matter which rapidly scale and clog the water supply pipe thereby, preventing filling of the water head. In order to avoid this condition the channels 15 are provided in the body 10 of the device and form jets for the passage of air. Said jets communicate with the casing 32 which in turn is directly connected to a blower fan indicated by the numeral 33. The fan when rotating causes a current of air to flow in the direction indicated by the arrow and passes upwardly thru the jets 15 where it draws up and mixes with the burning oil vapor in a similar manner to the steam above-described, and also aids atomization. The design of the device as shown in Figure 1 obviously permits both steam and air to be used simultaneously or selectively by independently operating either the air or water vapor systems. The device has been designed in the manner shown on the drawing with a view toward enabling the same to be readily dismantled when it is desired to clean any of the parts, and also for its facility in shipping and manufacture.

30 I claim:

1. A device of the class described comprising a main hollow annular body, legs on said body, the upper end of said legs having ridges thereon, said ridges being separated from the wall of said body by a channel, a conical shaped hood adapted to be seated in said channel, said hood having a relatively large opening at its upper end, said main body being adapted to receive fuel oil, a water head mounted above said hood, the flames of said oil being adapted to vaporize the water contents of said head, and means for conveying the water vapor to a position immediately above the surface of the oil.
2. A device of the class described comprising a main hollow annular body, legs on said body, ridges on the upper end of

said legs, said ridges being separated from the wall of said body by a channel, a conical shaped hood adapted to be seated in said channels, said hood having a relatively large opening at its upper end, said main body being adapted to receive fuel oil, a concentric funnel projecting upwardly from the bottom of said body having a divergently tapered opening therein, a water head mounted above said hood, the flames of said oil being adapted to vaporize the contents of said head, a pipe connecting said water head with the funnel, said pipe being adapted to convey the water vapor to a position above the surface of the burning oil, to aid in atomization of said oil, and means for conveying jets of air into the region above the surface of the oil.

3. A device of the class described comprising a main hollow annular body, legs on said body, ridges on the upper end of said legs, said ridges being separated from the wall of said body by channels, a conical shaped hood adapted to be seated in said channels, said hood having a relatively large opening at its upper end, said main body being adapted to receive fuel oil, a concentric funnel projecting upwardly from the bottom of said body having a divergently tapered opening therein, a water head mounted above said hood, the flames of said oil being adapted to vaporize the water contents of said head, a pipe connecting said water head with the funnel, said pipe being adapted to convey the water vapor to a position above the surface of the burning oil, semi-circular channels formed in the main body forming air jets, a casing beneath said main body communicating with said jets, an air blower connected to said casing adapted to force air thru said jets to the region above the oil, said air and water vapor being adapted to atomize the burning oil, and means for using said air and water vapor independently or simultaneously.

In testimony whereof, I affix my signature.

JOSEPH HEINZEL.
